UNITED STATES PATENT OFFICE.

WILLIAM H. JACK, OF GRAND RAPIDS, MICHIGAN, ASSIGNOR TO ORVILLE M. DUNHAM, OF SAME PLACE.

PAPER-HANGER'S BRUSH AND ROLLER COMBINED.

SPECIFICATION forming part of Letters Patent No. 387,562, dated August 7, 1888.

Application filed December 16, 1887. Serial No. 258,126. (No model.)

To all whom it may concern:

Be it known that I, WILLIAM H. JACK, a citizen of the United States, residing at Grand Rapids, in the county of Kent and State of Michigan, have invented certain new and useful Improvements in Paper-Hanger's Brush and Roller Combined; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a side view, and Fig. 2 is a top or plan view, of my invention.

Similar letters refer to similar parts.

I describe my invention as follows, viz:

A is the handle, made of wood or other suitable material.

B are bristles secured along the longitudinal face of the handle A.

E is a rectangular slot or recess formed in one end of the handle.

D is a screw-bolt on which the roller C is journaled in the slot or recess of the handle.

C is the roller journaled in the slot E on the screw-bolt D.

Having thus described my invention, what I claim as novel, and desire to secure by Letters Patent of the United States, is—

A combined paper-hanger's brush and roller comprising the handle having a rectangular slot or recess formed in one end, bristles secured along the longitudinal face of the handle, a screw-bolt, and the roller journaled thereon in the slot or recess of the handle, substantially as described.

In testimony whereof I affix my signature in presence of two witnesses.

WILLIAM H. JACK.
